United States Patent

Des. 239,875
Patented May 11, 1976

239,875

CONTAINER FOR EGGS OR THE LIKE

William J. Armstrong, Jeffersontown, Ky., assignor to
General Electric Company

Filed Apr. 1, 1974, Ser. No. 456,990

Term of patent 14 years

Int. Cl. D15—07

U.S. Cl. D67—3 B

FIG. 1

FIG. 4

FIG. 2

FIG. 3

FIG. 1 is an isometric view of the container for eggs or the like embodying my new design;

FIG. 2 is a top plan view thereof;

FIG. 3 is a sectional view taken along line 3—3 of FIG. 2;

FIG. 4 is a sectional view taken along line 4—4 of FIG. 2; and

FIG. 5 is a side view thereof with portions of the skirt removed for ease of illustration.

I claim:

The ornamental design of a container for eggs or the like, as shown and described.
